BAILER

William J. Flury, Long Beach, Calif., assignor of
one-third to Lewis P. Brandel and one-third to
Frank Halfen, Long Beach, Calif.

Application January 24, 1934, Serial No. 708,063

11 Claims. (Cl. 166—19)

This invention relates to well tools, such as employed in drilling or operating deep wells. The invention relates particularly to a valve and means for controlling the same. While features 5 of the invention may be employed for opening a valve at the bottom of the well for any special purpose, the invention is particularly applicable to a pressure bailer.

In this type of bailer the tool string carries 10 an air-tight chamber closed below by a valve. In the present invention, this valve is mounted on a seat so that by movement of the valve longitudinally of the axis of the tool, it moves off of its seat. The valve is opened automatically 15 when the bailer shoe strikes the bottom of the well. This releases the well pressure which exists within the lower portion of the bailer, and the liquid or gas in the lower portion of the bailer immediately escapes past the valve into 20 the air-tight chamber, which is at a relatively low pressure, such as atmospheric pressure. When this occurs, a reduced pressure is developed within the bailer with respect to the well pressure, and this causes a sudden inrush 25 of sand or other material from the well into the sand chamber of the bailer.

One of the objects of my invention is to provide simple means whereby a relative downward movement of the tool string will effect the opening 30 of the valve. In the preferred embodiment of the invention, the valve comes onto its seat by an upward movement from below, and this is advantageous because the pressure communicated from the well to the interior of the bailer, 35 assists in holding the valve on its seat until the time arrives for the valve to be opened. In accordance with my invention, I provide means for effecting a relative rotation of parts associated with the valve, and utilize this relative rotation for effecting the opening of the valve. This relative rotation is produced by the relative 40 downward movement of the tool string when the bailer shoe strikes the bottom of the well. When a tool of this kind is descending in a well, sometimes the shoe of the bailer may strike an obstruction, or due to a crooked hole its 45 downward movement may be resisted. If this occurs, it might cause a relative downward movement of the tool string, which would cause a premature opening of the valve. One of the 50 objects of the invention is to provide simple means of preventing such a premature opening of the valve.

Further objects of the invention will appear 55 hereinafter.

The invention consists in the novel parts and combination of parts to be described hereinafter, all of which contribute to produce an efficient bailer.

A preferred embodiment of the invention is 5 described in the following specification, while the broad scope of the invention is pointed out in the appended claims.

In the drawing:

Figure 1 is a side elevation of a tool string provided with a bailer embodying my invention, certain parts being broken away. 10

Figure 2 is a vertical section taken about along the line 2—2 of Fig. 1, and particularly illustrating details of my invention. In this view, sections of the tool string above and below are also 15 shown in section.

Figure 3 is also a vertical section somewhat similar to Fig. 2, but representing certain parts in cross section, that are shown in elevation in 20 Fig. 2. This view also merely illustrates the parts particularly associated with the valve.

Figure 4 is a view similar to Fig. 3, but with the valve seat and cam member shown in cross section. 25

Figure 5 is a cross section taken on the line 5—5 of Fig. 2, and particularly illustrating yieldable means for preventing premature opening of the valve when the bailer is descending in the well. 30

Figure 6 is a horizontal cross section on the line 6—6 of Fig. 3, and further illustrating details of the invention. 35

Figure 7 is a view illustrating a modified embodiment of the invention, and in this view one-half of the device is shown in full lines and one-half in cross section on the central axis of the tool.

Figure 8 is a vertical section taken through a cam sleeve and illustrating details of the same. This sleeve is employed in the embodiment of 40 the invention illustrated in Fig. 7.

Figure 9 is a vertical section through the outer sleeve, which is employed in both embodiments of the invention.

Figure 10 is a horizontal cross section on the line 10—10 of Figure 8. 45

Referring particularly to the parts and especially to Figure 1, I indicate a tool string, to be carried on a sand line, and the lower portion of which is provided with a mandrel section 2 on 50 which a casing 3 is mounted for telescoping movement, said casing being adapted for relative upward or downward movement on the tool string, but normally located in a relatively depressed position, that is to say, at the limit of its down- 55

ward movement. The upper portion of the tool string carries an air-tight chamber 4, and this chamber extends downwardly into the bore 5 of the section 2. The lower end of the casing 3 is connected by a coupling 6 to a tube section 7, which may be of any suitable length to provide a sand chamber 8 of sufficient volume to accommodate the sand which is to be taken by the bailer. The lower end of the section 7 carries a bailer 9 including a shoe 10 at the lower end of the bailer for engaging the sand, and through which the bailer is charged.

Referring now particularly to Figs. 2, 3 and 4, I provide within the casing or barrel 3, an actuator, 15 preferably in the form of an outer sleeve 11. In the present instance, this sleeve is made as an integral extension projecting up from the threaded neck 12 of the coupling 6 between the casing 3 and tube section 7. This sleeve is formed 20 preferably with two diametrically opposite helical slots 13 that extend downwardly into the sleeve from its upper edge. Within the sleeve 11 I provide valve opening means consisting of an inner member 14, which is preferably in the form of a cam sleeve, that is to say, it is provided with cam means for cooperating with the valve when a relative rotation of the valve and cam occurs, 25 to open the valve. This inner sleeve is therefore provided with a cam edge 15 (see Fig. 3), and this 30 cam edge engages with the upper side of a cross pin 16 carried by the stem 17 of the valve 18. The cam sleeve 14 preferably has two such cam edges 15 located diametrically opposite each other and cooperating with opposite ends of the cross 35 pin 16. The valve 18 comes upon its seat 19 by an upward movement, the said seat being provided in the present instance, at the lower end of the tool string section 2. In addition to the helical slots 13, the sleeve 11 is provided with two diametrical- 40 ly opposite straight slots 20, and these slots are engaged by the ends of the pin 16. The cam sleeve 14 is provided with rigid means such as "buttons" 21, (see Fig. 3) to run in the helical slots 13. A coil spring 22 within sleeve 14 normally holds 45 the valve on its seat.

In the operation of the tool, the downward movement of the tool string will embed the shoe 10 in the sand. The sand will prevent rotation of the shoe. A further downward movement of the tool string with respect to the casing 3, will cause the buttons 21 to rotate as they descend in the slots 13, that is to say, these buttons will cause a rotation of the cam sleeve 14 on its longitudinal axis, and will at the same time, rotate the 50 tool string. But the pin 16 traveling in the straight slots 20, will prevent rotation of the valve 18 on its axis, and hence a relative rotation of the valve and cam sleeve 14 will occur. In this way, the cam edges 15 will move the valve down 55 and off of its seat. This will open the valve suddenly, whereupon the well pressure which exists within the sand chamber 8, will be suddenly released up into the air-tight chamber 4. This will cause a sudden inrush of sand and material 60 through the bailer shoe, and in this way charge the bailer. This sand will be retained in the sand chamber by the usual check valve 23, (see Fig. 1).

In lowering a tool of this kind down a well, the contact of the shoe with the well casing may 65 tend to cause a premature relative upward movement of the casing 3 on the tool string, which might cause a premature opening of the valve. In order to meet this contingency, I provide means for yieldingly holding the casing 3 in a 70 relatively depressed position on the section 5.

For this purpose I prefer to provide the section 2 with a spring ring 24 (see Figs. 2 and 5). This spring ring is carried under a circumferential shoulder 25 in the section 2, and is received in a counterbore 26 in the upper end of a split sleeve or 5 nut 27 that screws into the upper end of the casing 3. Just below the counterbore 26 an inclined shoulder 28 is formed. The spring ring 24 is a split ring which can collapse under the shoulder 25 sufficiently to enable the spring ring 10 to pass down into the bore of the split sleeve 27. However, in order to collapse the ring in this way, it would require considerable downward pressure exerted at the shoulder 25, such for example, as the weight of the tool string. 15

In addition to this spring ring 24, I prefer to provide a regular flat coil spring 29 around the section 2 within the casing 3, and the lower end of this spring thrusts against the upper end of the sleeve 11. The upper end of this spring 20 thrusts against the lower packing collar 30 of a series of collars 31 that are formed on the section 2. The uppermost collar of these collars is engaged by the lower end of the split sleeve 27, and this limits the downward movement of 25 the casing 3 on the tool string. In order to facilitate access to the spring 29, the section 2 of the tool string is preferably formed of an upper piece 2a and to this upper piece the cam sleeve 14 is 30 rigidly connected by a tight threaded joint 2c.

In Figs. 7 and 8, I illustrate another embodiment of the invention in which the valve is not prevented from rotating as it lifts off its seat, but I simply pull the valve off its seat while permitting it to rotate. Referring to these Figures 7 and 8, 32 indicates the casing corresponding to the casing 3, and 33 indicates the lower portion of an outer sleeve corresponding to the sleeve shown in Fig. 9, and this sleeve 33 is rigidly secured by threads 32a to the casing 32. This 40 sleeve 33, however, has no straight slots, but has a pair of diametrically opposite helical slots, each of which is engaged by a corresponding end of the cross pin 34 carried by the valve 35. Within the outer sleeve 33 an inner cam sleeve 36 is 45 provided, constructed as illustrated in Fig. 8. This sleeve is rigidly secured to the lower end of a mandrel 36a by screw threads. This mandrel 36a corresponds to the mandrel 2 of Figs. 1 to 3. This sleeve has two diametrically opposite cam slots 37 through which the ends of the pin 34 pass. With this organization of parts, it will be evident that when the tool string moves downwardly relative to the casing 32, the pins 34 descending in the helical slots corresponding to the 50 slots 13, will cause the rotation of the valve 35 on its longitudinal axis. This will cause the pins 34 to move along the cam slots 37, thereby pulling the valve open. The inner sleeves such as the sleeve 36 and the sleeve 14, are formed with side 55 openings such as the openings 38 and 39 (see Fig. 8), and the lower end of the sleeve is formed with an integral cross bar such as the cross bar 40 shown in Fig. 10. This cross bar is of reduced width so as to provide an opening 41 at each side, through which the oil or water can pass upwardly 60 through the sleeve before it reaches the valve. 65

At a suitable point, preferably at an elevated point in the air-tight chamber 4, a relief valve 70 42 is provided as indicated in Fig. 1.

In order to discharge the bailer after it is withdrawn from the mouth of the well, the bailer may be provided with the usual rotatable sleeve 43 having a side opening 44, which may register 75

with an orifice 45 in the side of the bailer, (see Fig. 1).

If desired, this bailer can be used for spudding in a well that is not under pressure.

5 It is understood that the embodiment of the invention described herein, is only one of the many embodiments this invention may take, and I do not wish to be limited in the practice of the invention, nor in the claims, to the particular 10 embodiment set forth.

What I claim is:—

1. In a pressure bailer, the combination of a tool string having a closed air-tight chamber, a bailer casing carried on the lower end of the tool 15 string and having a sand chamber with a shoe at its lower end for engaging the well bottom, said casing mounted on the tool string for telescoping upward movement and normally occupying a relatively depressed position on the tool string, a 20 valve seat, and a valve at the lower end of the air-tight chamber capable of moving longitudinally of the casing for closing off communication between the same and the sand chamber while the bailer is descending within the well, a 25 sleeve within the bailer casing having a helical guide slot, means associated with the valve, brought into action by relative upward movement of the casing when the shoe strikes the well bottom, to cooperate with said helical slot for effecting a relative rotation of the valve and the last 30 named means for moving the valve longitudinally of the casing to move the same off of its seat, thereby releasing the pressure in the sand chamber, and causing an inrush of sand and material 35 from the well into the sand chamber.

2. In a pressure bailer, the combination of a tool string having a closed air-tight chamber, a bailer casing carried on the lower end of the tool string and having a sand chamber with a shoe at 40 its lower end for engaging the well bottom, said casing mounted on the tool string for telescoping upward movement and normally occupying a relatively depressed position on the tool string, a valve seat, and a valve at the lower end of the 45 air-tight chamber capable of moving longitudinally of the casing for closing off communication between the same and the sand chamber while the bailer is descending within the well, a sleeve within the bailer casing having a helical 50 guide slot, cam-means carried at the lower end of the tool string engaging the valve brought into action by relative upward movement of the casing when the shoe strikes the well bottom, to cooperate with said helical slot and the valve for 55 moving the valve longitudinally of the casing to move the same off its seat, thereby releasing the pressure in the sand chamber and causing an inrush of sand and material from the well into the sand chamber.

60 3. In a pressure bailer, the combination of a tool string having a closed air-tight chamber, a bailer casing carried on the lower end of the tool string and having a sand chamber with a shoe at its lower end for engaging the well bottom, said casing mounted on the tool string for telescoping upward movement and normally occupying a relatively depressed position on the tool string, a valve seat, and a valve at the lower 65 end of the air-tight chamber capable of moving longitudinally of the casing for closing off communication between the same and the sand chamber while the bailer is descending within the well, a sleeve within the bailer casing having a helical 70 guide slot, a cam-member mounted at the lower end of the tool string, said valve having

means for engaging the cam-member, said sleeve, valve and cam-member cooperating when the shoe strikes the well bottom and moves the casing relatively upwardly, to effect a relative rotation of the valve and cam-member through the 5 agency of said helical slot to move the valve longitudinally of the casing and off of its seat, thereby releasing the pressure in the sand chamber and causing an inrush of sand and material from the 10 well into the sand chamber.

4. In a pressure bailer, the combination of a tool string having a closed air-tight chamber, a bailer casing mounted for longitudinal movement on the lower end of the tool string and having a sand chamber with a shoe at its lower end for 15 engaging the well bottom, said casing normally occupying a relatively depressed position on the tool string, a valve seat, and a valve cooperating with said seat for closing off communication between the air-tight chamber and the sand 20 chamber while the bailer is descending within the well, a sleeve within the bailer casing having a helical guide slot and having a straight guide slot extending longitudinally with respect to the axis of the bailer, a cam in the form of a sleeve 25 carried by the tool string and having means for engaging the helical slot to cause rotation of the cam sleeve, said valve having means rigid therewith and guided in the said straight slot, said 30 valve having a part for engaging the cam, said sleeve, cam and valve cooperating so that when the bailer shoe strikes the well bottom and is arrested thereby the relative downward movement of the tool string with respect to the shoe will effect rotation of the cam sleeve relative to the 35 valve to move the valve off its seat, thereby releasing the pressure in the sand chamber and causing an inrush of sand and material from the well into the sand chamber.

5. In a pressure bailer, the combination of a 40 tool string having a closed air-tight chamber, a bailer casing carried on the lower end of the tool string, having a sand chamber with a shoe at its lower end for engaging the well bottom, said casing 45 mounted on the tool string for relative upward telescoping movement, a spring associated with said casing for normally holding the same in a depressed position on the tool string, a valve seat, a valve capable of vertical movement carried at the lower end of the air-tight chamber 50 for closing off communication between the air-tight chamber and the sand chamber, a spring for normally holding the valve on its seat while the bailer is descending within the well, a sleeve within the bailer casing having a helical 55 guide slot and having a straight guide slot substantially parallel with the axis of the bailer, a cam sleeve associated with the first-named sleeve and having means running in the helical slot, said valve having a rigid cross pin running in 60 the straight slot, and engaging the cam of the cam sleeve, said first-named sleeve, said cam-sleeve and said valve cooperating when the shoe strikes the well bottom so that the relative downward movement of the tool string with respect to the shoe, will effect a relative rotation of the cam sleeve and the valve to move the valve off of its seat, thereby releasing the well pressure within the sand chamber and causing an inrush of sand and material from the well into 65 the sand chamber.

6. In a pressure bailer, the combination of a tool string having a closed air-tight chamber, a bailer casing carried on the lower end of the tool string and having a sand chamber with a shoe at 75

its lower end for engaging the well bottom, said casing mounted on the tool string for relative upward telescoping movement and normally occupying a depressed position on the tool string, a valve seat, and a valve at the lower end of the air-tight chamber capable of moving longitudinally of the casing for closing off communication between the same and the sand chamber while the bailer is descending within the well, a sleeve within the bailer casing having a helical guide slot, means associated with the valve and cooperating with said helical slot for effecting a relative rotation between said means and said valve for moving the valve longitudinally of the casing to move the same off of its seat, thereby releasing the pressure in the sand chamber, and causing an inrush of sand and material from the well into the sand chamber, a spring for normally holding the casing in its depressed position on the tool string, and means other than the said spring for yieldingly resisting relative upward movement of the said casing on the tool string while the bailer is descending in the well, to prevent accidental upward movement of the casing relative to the tool string and premature opening of the valve.

7. In a pressure bailer, the combination of a tool string having a closed air-tight chamber, a bailer casing carried on the lower end of the tool string and having a sand chamber with a shoe at its lower end for engaging the well bottom, said casing mounted on the tool string for relative upward telescoping movement and normally occupying a depressed position on the tool string, a valve seat, and a valve at the lower end of the air-tight chamber capable of moving longitudinally of the casing for closing off communication between the same and the sand chamber while the bailer is descending within the well, a sleeve within the bailer casing having a helical guide slot, means associated with the valve and cooperating with said helical slot for effecting a relative rotation between said means and said valve for moving the valve longitudinally of the casing to move the same off of its seat, thereby releasing the pressure in the sand chamber, and causing an inrush of sand and material from the well into the sand chamber, said tool string having a section carrying the said casing, a collapsible spring ring carried on said section for engaging the upper end of the casing for yieldingly resisting downward movement of the tool string relative to the casing to prevent premature relative upward movement of the casing and premature opening of the valve, said spring ring operating to collapse when the bailer shoe strikes the well bottom to permit downward movement of the tool string relative to the casing.

8. In a pressure bailer, the combination of a tool string having a closed air-tight chamber, a bailer casing carried on the lower end of the tool string and having a sand chamber with a shoe at its lower end for engaging the well bottom, said casing mounted on the tool string for relative upward telescoping movement and normally occupying a depressed position on the tool string, a valve seat, and a valve at the lower end of the

air-tight chamber capable of moving longitudinally of the casing for closing off communication between the same and the sand chamber while the bailer is descending within the well, a sleeve within the bailer casing having a helical guide slot, said sleeve also having a straight guide slot substantially parallel with the longitudinal axis of the bailer, a cam sleeve within the first-named sleeve, said valve having a cross pin engaging the cam of the cam sleeve and running in the helical slot, said first-named sleeve, said cam-sleeve and said valve cooperating so that when the shoe strikes the well bottom and the tool string downward with respect to the shoe, the rotation of said valve by the helical slot, relative to the cam sleeve, will move the valve off its seat, thereby releasing the pressure in the sand chamber and causing an inrush of sand and material from the well into the sand chamber.

9. In a well tool, the combination of a tool string having a valve seat and a valve carried thereon, an outer sleeve having a helical guide slot and having a straight guide slot extending substantially parallel with the axis of the tool, and a cam-member carried at the lower end of the tool string, associated with the sleeve, said valve having a part running in one of said slots, and said cam member having a part running in the other slot, said valve engaging the cam and all of said parts cooperating so that upon a downward movement of the tool string with respect to the first-named sleeve, the valve and the cam sleeve will be given a relative rotation to move the valve longitudinally of the tool string and off its seat.

10. In a well tool, the combination of a tool string, a casing carried by the tool string, a valve seat, a valve carried within the casing, capable of vertical movement, an outer sleeve within the casing and rigid therewith, having a helical guide therein and having a straight guide extending substantially parallel to the axis of the tool, and an inner cam sleeve within the outer sleeve, said valve having means for running in one of said guides, and said cam sleeve having a part running in the other of said guides, all of said valve, said outer sleeve, and said cam-sleeve cooperating so that a downward movement of the tool string with respect to the casing and the outer sleeve, will effect relative rotation of the valve and cam sleeve and move the valve off its seat.

11. In a pressure bailer, the combination of a bailer casing, a shoe mounted to slide relatively upwardly on the bailer casing when the shoe strikes the well bottom, a valve seat and a valve on the seat capable of moving longitudinally of the casing to open the valve, opening means for opening the valve, said valve and said opening means being relatively rotatable with respect to each other, and actuating means carried by the shoe operating when the shoe strikes the well bottom and moves relatively upwardly on the casing, to effect a relative rotation of the valve and said opening means, to open the valve.

WILLIAM J. FLURY.
